UNITED STATES PATENT OFFICE.

HERMAN B. PHILIPS, OF NEW YORK, N. Y.

STRETCHER FOR FLUOROSCOPY.

Application filed September 4, 1923. Serial No. 660,762.

To all whom it may concern:

Be it known that I, HERMAN B. PHILIPS, a citizen of the United States, residing at New York city, borough of Manhattan, in the county of New York and State of New York, have invented certain new and useful Improvements in Stretchers for Fluoroscopy, of which the following is a specification.

10 This invention relates to hospital apparatus or surgical appliances and has particular reference to mechanisms or apparatus for the reduction of broken bones and the detection or correction of any malposition or deformity incident to such cases.

15 Among the objects of the invention is to provide a combined fracture stretcher and table designed to reduce deformities or malposition of fragments of broken bones under fluoroscopic guidance,—both in horizontal and vertical planes, and either alone or simultaneously; to afford means for traction on any limb or extremity at any angle, and with any desired counter traction or traction 20 or pressure at any angle to the main traction; to provide means as set forth in the foregoing to reduce deformities from fractures or disease and retain them in any desired position while immobilizing firmly in 25 plaster casts or splints; to provide a stretcher on which a patient may be supported not only for the purpose of the application of the traction and reducing operations above referred to but also upon which he may be moved for the purpose of fluoroscopy or 30 radiography, but especially to provide means whereby the observation through fluoroscopy or the making of records through the radiographic or roentgenographic steps may 35 be practiced at the same time that the reduction of the bones or the like is taking place so that the operator may be guided in his operations by the visual results obtained 40 through either of the means just referred to, and, furthermore, the stretcher mechanism combined with the traction means insures that the traction may be maintained or 45 preserved irrespective of the movement or manipulation of the stretcher with the patient thereon.

50 A still further object of the invention is to provide a stretcher having traction apparatus associated therewith and so designed as not to obstruct either the fluoroscopic vision or the radiographic fields at any time.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a side elevation showing one adaptation of my improvement.

Fig. 2 is a plan view of the same.

Fig. 3 is a sectional detail on the line 3—3 of Fig. 1.

Fig. 4 is a plan view of a detail described in connection with Fig. 5.

Fig. 5 is a vertical detail partly in section of the crotch mechanism.

Fig. 6 is a detail perspective view of the transformer mechanism for the horizontal fluoroscopy, its means of support, and the vertical and horizontal screens carried thereby.

Referring now more specifically to the drawings I show a frame or stretcher comprising two side bars 10, two end bars 11, and corner connections 12. These corner pieces may constitute or carry handles 13 for manipulating the stretcher as such, in a well known manner. The side rails 10 and either or both of the end rails are provided with vertical holes 14 spaced at regular intervals from one another. The end rails or at least one of them are open ended for the accommodation of slidable rods 15 which normally telescope or may be drawn outward to any desired length and locked as by means of a spring pin 16 or its equivalent through the adjacent corner pieces for fixing the position of the extensions. The corner pieces may have downward extensions 12' serving as feet for supporting the stretcher.

17 indicates a plate shown as substantially rectangular and extending across the stretcher and supported at its ends on the side rails 10 and along which the plate is movable endwise of the device, the ends of the plate being turned downward around the rails for self retention. As indicated this plate constitutes the main support or bridge for supporting the patient's hips through a disk or shelf 18 fixed adjustably upon the upper end of the pedestal 19. That is to say, the disk may be swung

around the axis of the pedestal to lie either longitudinally or transversely of the stretcher according to its immediate purpose. 20 indicates the crotch piece or pin detachably connected as by threads 21 in the upper end of the pedestal and may serve as a binding means or lock for holding the disk from rotation. The upper end of the crotch pin is screw threaded to receive a 10 stem 22 for holding one or more horizontally extending arms 23 having slides or brackets 24 for such purposes as supporting traction or counter traction means or bandages or slings such as indicated at 25. The disk 15 18 may be used as a support for the hips as shown or may be used for other purposes such as a clamp for the patient's shoulder and for this purpose the patient may be supported at the same level as indicated in 20 Fig. 1 or may be lowered to the plane of the stretcher frame. In the former case the disk or shelf 18 may be clamped between the crotch pin and the stem 22 or it may be otherwise attached to the pedestal. 25 30 35 40 45 50 55 60 65 70 75 80 85 90 95 100 105 110 115 120 125 130

26 indicates a bed plate of wood of any suitable composition and which like the plate 17 is preferably transparent to Roentgen rays. The bed plate 26 is rectangular and supported for endwise adjustment upon the rails 10. Pillows or padding 27 will be employed for their usual purpose in bolstering up the patient at any desired point.

The pedestal is connected adjustably to the plate 17 as by means of bolts 28 co-operating with slots 29. The plate 17 is held from endwise movement under traction on the patient along the stretcher as by means of clamps 30 adjustable along the rails 10.

In connection with the stretcher frame 40 or extensions thereof I employ one or more traction units 31 each comprising an arm 32 adjustable vertically in a clamp 33 carried by either end or side bar of the frame, though usually it is connected to the foot 45 rail 11 for the reduction of a broken leg. The unit includes also a nut or head 34 along which a threaded shank or screw is slideable but held from rotation by any well known means such as a spline. The traction is 50 produced by means of a hand wheel 36 or its equivalent co-operating with the threaded screw and bearing against the head 34 in a well known manner. The extremity, as the foot, of the 55 patient is secured, as by bandaging or lacing, to a yoke or clamp piece 37 having universal ball joint connection in a clamp 38 fixed to the adjacent end of the screw 35. The open structure of the yoke provides for 60 easy access to the patient's extremity for the purpose indicated. The clamp 33 may be secured to the rail either by means gripping the same or by means of pins passing therethrough and through the holes 14. For attaching the unit or any of them to the frame

extensions 15 a clamp 33' may be employed. This provides an anchorage for the traction unit at an angle to the length of the stretcher for use in connection with lateral traction or for other purposes. As thus far described the stretcher is free and open for not only the purposes of the traction apparatus and bandaging of the patient, but also for observation as soon to be described. Moreover, with the patient in position on the 75 stretcher and even with the traction apparatus in use under tension the stretcher may be transported or manipulated in any convenient manner.

As an illustration of the many accessories, I indicate at 39 a form of clamp adapted especially for connection to and interlocking with the perforated rails of the stretcher. Extending upward from this clamp and gripped thereto by a hand piece 40 is a post 41 which obviously may be adjusted around its own axis in the clamp as may be desired. At the top of this post is a hub 42 in which is adjustably mounted a horizontal arm 43 and locked as by means of a set screw 44. At one end of this arm is a clamp or joint 45 which carries an arm 46 adjustable in any desired angle with respect to the arm 43 and in all other respects taking into consideration the manner of connecting the arm 43 to the post, and the post in turn to the clamp 39. The arm 46 may be provided with any suitable form of yoke 47 for use for traction, counter traction, or other analogous purposes, and having practically universal joint connection with the main support has a wide range of adjustment anywhere along the stretcher and at any position after being so adjusted.

Another important feature of my mechanism comprises a table having a top 48, corner uprights or legs 49, and a plurality of longitudinal bars not only for stiffening the table, but for purposes soon to appear. Some of these bars, as indicated at 50, extend lengthwise along the sides of the table approximately midway between the floor and the top 48 and in the same horizontal plane. 51 indicates conventionally an X-ray apparatus or transformer mounted slidably 110 upon a pair of transverse rails 52, said rails being mounted upon runners or shoes 53 co-operating directly with the rails 50, so that the apparatus as a whole may be moved bodily endwise of the rails 50 and also independently of the rails 50 transversely of the table along the rails 52 so as to bring the transformer 51 beneath any point or part of the table top. The action of this transformer is upward or vertical through the table top and through the patient. Hence it is designed to give an image directly upon the horizontal screen 51^a or for the making of a radiograph upon a plate similarly located above the patient.

At either side of the table is a carriage 54 comprising a pair of vertical hollow posts 55 with any suitable tie bars 56 between them. This carriage is mounted upon a rail 58 near the floor. The posts at any convenient place as just below the table top are provided with hangers 59 which extend beneath the table top and carry pairs of rollers 60 which embrace a bar 61 extending 10 between the corner posts 49 of the table. Thus the carriage 54 is movable freely along the rails 58 and 61 and consequently at any desired position along the table from one end to the other. 62 indicates a second 15 X-ray tube or transformer supported upon a pair of horizontal arms 63 extending through a similar number of sleeves 64 slideable or movable up and down along the posts 55. The arms 63 are movable laterally so as to 20 position the transformer 62 at any desired position with respect to the center of the table and it of course is movable along the posts as well as with the posts or carried longitudinally of the table. This transformer 25 is designed to throw the image horizontally where it may be observed on the vertical screen 62^a or a plate may be made at such position for a radiograph. As shown in Fig. 6 the screens are connected to a frame 30 65 slideable horizontally in guide ways 66 at the top of the transformer 62 so that the screen 51^a may be moved directly over the transformer 62. The screen 62^a is hinged at 67 to the other screen or its frame 35 and may be swung upward into the same plane as the screen 51^a where it may be locked by spring catches 68 or their equivalent. With the two screens adjusted as 40 shown in Fig. 6 the operator or surgeon may observe fluoroscopically on either or both of the screens simultaneously the image thrown upward and horizontally from both of the transformers while at work upon the patient. Obviously, after the reduction has 45 been completed the transformer 62 may be moved out of the way for the purpose of facilitating the bandaging of the extremity. The transformer 62 is counter balanced in a well known manner by the use of suspending cables 69 to the other ends of which are counter weights 70 movable within the posts.

From the foregoing it will be appreciated 50 that the objects above indicated are attained in a practical apparatus, and by means of the universality of the various devices and connections the extremity or any part of the patient can be put and kept in any position, such as flexion, extension, inversion, eversion, abduction, or adduction. It will be appreciated also that the apparatus, having reference especially to the fluoroscopic facilities, may be utilized for general diagnosis, as for the localization of any 55 foreign body or particles that may seem to

be present in the body, and independently of reduction of fractures.

I claim:

1. The combination with a main support having a plurality of corner posts, of a 70 stretcher body consisting of a plurality of rails, said rails being united to each other by corner connections, said corner connections having downward extensions to co-operate with said corner posts to retain 75 said stretcher body in predetermined position thereon, said corner connections having handles extending along the plane of the stretcher and outwardly thereof whereby said stretcher may be lifted from said 80 support while a patient reposes thereon.

2. In a stretcher of the character set forth, the combination of a frame including side and end rails, traction means secured to one 85 of said rails, and counter traction devices including a plate adjustable transversely of the side rails and an engagement member for the patient projecting upward from and having rigid connection with the plate, adjustable clamping devices being provided 90 co-operating with the side rails and said plates for supporting and holding the plate in adjusted position for resisting the traction and to permit the plate to be moved 95 transversely of the rails as aforesaid.

3. A stretcher of the character set forth comprising, in combination, a frame composed of pairs of parallel rails and corner pieces connecting them each to each, traction and counter devices carried by the stretcher rails, and an accessory for additional traction or counter traction, said accessory comprising a clamp adjustable along 100 one of the rails, an upright support connected thereto, an arm movably connected to said support, and a yoke having universal connection with said arm.

4. In a device as set forth, the combination with a stretcher having side rails and traction means adapted to act at an angle to the stretcher, of a rod located at an end of the stretcher and slideable transversely relative thereto within a rail thereof and beyond the side of the stretcher, and means borne 105 upon the rails co-operating with the rod to hold it adjustably in position as aforesaid, said rod being adapted to adjustably engage said traction means along the length thereof for the purpose of the angular traction aforesaid.

5. The herein described counter traction devices for stretchers, the same comprising a plate, means to fix the position of the plate with respect to the stretcher, a pedestal extending upward from the plate, a disk for the top of the pedestal, and a crotch pin serving to clamp the disk to the pedestal, and extending upwardly of said disk.

In testimony whereof I affix my signature.
HERMAN B. PHILIPS.
